RAILWAY BLOCK-SIGNAL AND TRAIN-CONTROLLING SYSTEM.

1,095,982.

Specification of Letters Patent.

Patented May 5, 1914.

Application filed January 9, 1911. Serial No. 601,643.

To all whom it may concern:

Be it known that I, GEORGE R. GUILD, a citizen of the United States, and first lieutenant, Eighth Infantry, United States Army, stationed at Fort Leavenworth, Kansas, have invented a certain new and useful Improvement in Railway Block-Signal and Train-Controlling Systems, of which the following is a full, clear, and exact description, 5 such as will enable others skilled in the art to which it appertains to make and use the same, reference being had to the accompanying drawings, forming part of this specification.

15 This invention relates to an improved railway track signal and train controlling system and broadly stated; comprises, first; the railway track, its switches, sidings and crossings arranged, equipped and wired as hereinafter more fully described; second; the railway station equipped with devices properly connected for (a) the recording of the passage of trains over the blocks connected to the station; (b) the stopping of a train 20 on any block by the station agent; (c) telephonic communication between the engineer of a locomotive on any block, and the station agent; third; the engine carrying (a) the shoes which travel upon and make contact 25 with the track rails and the third rail; (b) the signaling devices for the engineer; (c) the switch which controls the flow of current through the various circuits; (d) the automatic air brake setting and steam cut off 30 appliances; and (e) the engineer's telephone.

The principal objects of my invention are, first; to warn the engineer of a moving train when two blocks away from a block occupied by a train; second; to warn the engineer 35 when his locomotive runs onto a block occupied by a train and to apply the air brakes and shut off the steam to the cylinders of the locomotive, should the engineer fail to notice the warning signal; third; to warn the engineer when his locomotive is about to run into a switch improperly set; fourth; to automatically register in a way station the passage of trains over the blocks connected to said station; fifth; the maintenance of the 45 registering signal in the station during the entire time the train is on the block; sixth; the indicating in the station the direction in which a train is moving, and which indication takes place where the batteries or a dynamo is carried by the engine; seventh; to provide means whereby the station master

may stop a train on any block, and put himself in telephonic communication with the engineer of the train so stopped, and, eighth; to do away with the necessity for exterior 60 semaphores and signaling devices by the location of all signals in the engineer's cab and in the station agent's office.

Figure 1 is a diagrammatic view illustrating the wiring, switches and signaling devices carried on the locomotive, and also showing the track rails, the third rail, and the shoes which travel upon said rail. Fig. 2 illustrates a locomotive in dotted lines with the signal board positioned in the locomotive cab and the third rail shoe and switch box carried by the forward truck of the locomotive. Fig. 3 is a vertical section taken through the center of the box or housing in which is located the switch that is controlled 75 by the shoe operating on the third rail. Fig. 4 is a vertical section taken on the line 4-4 of Fig. 3, with the parts in the positions they occupy while the shoe is on the normal elevation of the third rail. Fig. 5 is a section 79 similar to Fig. 4 and showing the shoe on the highest elevation of the third rail, and with the main switch in the box or housing in its uppermost position. Fig. 6 is a section similar to Figs. 4 and 5 and showing 85 the shoe on the lowest elevation of the third rail, and the main switch in the box or housing in its lowermost position. Fig. 7 is a side elevation of a portion of the third rail with parts broken away to economize space. 90 Fig. 8 is a diagrammatic view of a portion of a single track wired in accordance with my invention and showing the station connections, switches and indicators for four blocks of the track, and also showing one 95 block not controlled by the station. Fig. 9 is a diagrammatic view of a double track arranged and wired in accordance with my invention. Fig. 10 is a diagrammatic view of a switch or siding arranged and wired in accordance with my invention. Fig. 11 is a diagrammatic view of a crossing arranged and wired in accordance with my invention. Fig. 12 is a diagrammatic view of a portion of a track with the batteries located in the 10 track wiring, and the high resistance on the engine. Fig. 13 is a diagrammatic view similar to Fig. 12 and illustrating the high resistance placed in the track wiring and the battery on the engine. Fig. 14 is a diagrammatic view of a track relay located in the connections between the bonded track rail

and the sectional track rail. Fig. 15 is a diagrammatic view similar to Fig. 14, and illustrating the connections whereby the relay circuits are established. Fig. 16 is a diagrammatic view illustrating the relays properly connected to crossing track rails.

The track, its connections and the station with its connections and indicators will first be described.

10 Referring to Fig. 8 it will be noted that one of the track rails A^1 is made practically continuous by the bonding together of the meeting ends of the track rails while the opposite rail A^2 is divided into blocks or sections of any desired length, and the ends of the blocks or sections are insulated from one another. A third rail A^3 extends the entire length of the track and is divided into sections which are insulated from one another as shown by the open spaces between the sections of said third rail, and these various sections are arranged at different elevations for the purpose of raising and lowering the main switch carried on the locomotive, and hereinafter more fully described. The plain unshaded portions A^4 designate the normal elevation of this third rail, and which elevation is slightly higher than the plane occupied by the tops of the track rails, in order to permit the shoe traveling on the third rail to readily pass over crossings and switches without coming in contact with the main track rails. The portions A^5 of the third rail occupy a higher elevation than the normal portions A^4 and the shaded portions A^6 occupy an elevation lower than the plane occupied by the normal portions A^4 . This arrangement of the various elevations of sections of the third rail is clearly shown in Fig. 7 where the dotted line $X-X$ indicates the normal elevation or plane occupied by said third rail.

In Fig. 8 insulation between the various sections of the third rail is denoted by the breaks or openings between the sections, and in Fig. 7 the insulation is shown in the usual manner. The blocks or sections of the track rail A^2 are connected to the opposite track rail A^1 , and located in these connections are batteries A^7 , resistance coils A^8 and magnet relays Q , as diagrammatically illustrated in Figs. 14 and 15. These magnet relays are connected and arranged for operation in pairs or groups in such a manner that when the current is passing through one magnet of any pair or group the circuits through all of the other magnets of that pair or group are open or broken, due to the fact that the circuit of any magnet of a pair or group must pass through the proper contact points on each of the armatures of the other magnets of the pair or group, and not through the armature of the first mentioned magnet. (See Figs. 14 and 15.) The station wiring and equipment shown diagrammatically in

Fig. 8 includes controlling means for blocks 2, 3, 4 and 5 of the track. The station equipment includes four indicators B^2 , B^3 , B^4 and B^5 corresponding respectively to blocks 2, 3, 4 and 5, and arranged adjacent these indicators are hand switches C^2 , C^3 , C^4 and C^5 . These hand switches are adapted to engage in sockets D^2 , D^3 , D^4 and D^5 , which sockets are electrically connected with the corresponding indicators B^2 , B^3 , B^4 and B^5 . Leading from the indicators in the station are branch lines B^6 , which connect with a single line B^7 leading to the continuous track rail A^1 . The hand switches C^2 , C^3 , C^4 and C^5 are connected respectively by lines D^6 , D^7 , D^8 and D^9 with the blocks 2, 3, 4 and 5 and located in these lines are batteries a^2 , a^3 , a^4 and a^5 . Arranged adjacent the hand switches is a series of sockets E^2 , E^3 , E^4 and E^5 , which sockets are electrically connected to a circuit E^6 in which is located a telephone E^7 , the opposite end of said circuit being connected to the line B^7 . The circuit E^6 is normally open, by reason of the normal position of the hand switches C^2 , C^3 , C^4 and C^5 , and of the weight of the receiver on the hook, which acts as a switch in the usual manner. The normal sections of the third rail of each block are electrically connected by means of wires F^1 to the rails A^2 of the next adjacent blocks in both directions. The lower sections A^6 of one of the blocks of the third rail are electrically connected by wires F^2 to the corresponding lower sections A^6 of the next adjacent blocks in both directions, and in the same manner the highest portions A^5 of each block are electrically connected by means of wires F^3 to the corresponding higher sections A^5 of the next adjacent blocks in both directions.

Referring now to Figs. 1 to 6 inclusive, which illustrate the parts of the apparatus carried upon the locomotive, 1 designates the shoe which is adapted to ride upon the third rail, said shoe being pivotally mounted on the lower end of a vertically disposed rod 1^a , which extends through a bearing in the bottom of a box 1^b , located at a suitable point on the locomotive, preferably on a frame carried by the front trucks. Located on the rod 1^a between the shoe and the under side of the box is an expansive coil spring 1^c , which normally forces the shoe into contact with the third rail. A lever 1^d is fulcrumed at a suitable point on the locomotive, and one end of said lever is connected to the lower part of the rod 1^a . This lever is manipulated by means of a hand lever 1^e , and thus the rod 1^a can be elevated, when desired to lift the third rail shoe free of the third rail. P designates the main switch bar or rail which is hinged within the box 1^b , and which switch bar carries a series of knife blade switch arms 8, 9, 10, 11 and 12. When the main switch bar P is swung down-

ward to its limit of movement the plates 8, 9, 11 and 12 enter respectively, sockets 4, 5, 6 and 7 arranged within the box, and when said switch bar is moved to its upper limit 5 of movement the blades 8, 10, 11 and 12 enter respective sockets 13, 14, 15 and 16 arranged within the box above the series of sockets heretofore described. P^1 designates an arm carried by and extending upward 10 from the upper end of the rod 1^a, and the central portion of said arm is arranged to slide loosely through the main switch bar P . Shoulders P^2 are formed on the arm P^1 and are adapted to engage the switch 15 bar P and move the same upward or downward, corresponding to the movement of the shoe 1 on the third rail. Carried by the upper end of the arm P^1 is a contact finger 18 adapted to make contact with a pair of 20 plates 17 and 19 arranged on the rear wall of the box 1^b. α designates a locking finger in the main switch box, the rear end of which locking finger is carried by a pair of curved arms α^1 fulcrumed at α^2 with their forward 25 ends in the path of travel of a pair of pins α^3 carried by the arm P^1 and located above and below the shoulders P^2 . An expansive coil spring α^4 connected to the rear end of the locking finger normally forces the same 30 forward into position above or below the main switch bar P :

In Figs. 3 and 4 the various parts of the main switch are shown in their normal positions, and in the positions they occupy while 35 the shoe 1 is on the normal portions A^4 of the third rail. It will be noted that the switch bar P is elevated so as to make contact with the sockets 13, 14, 15 and 16 and said switch bar is locked against downward 40 movement by the locking finger α , which occupies a position beneath said switch bar. With the parts so positioned the contact finger 18 occupies a position between the contact plates 17 and 19. When the shoe 45 1 moves onto the higher parts A^5 of the third rail, the arm P^1 is moved upward as shown in Fig. 5 and the finger 18 makes contact with the plate 19. When the shoe 50 moves onto the lowest portions A^6 of the third rail the parts occupy the positions seen in Fig. 6 with the main switch bar P moved downward to make contact with the sockets 4, 5, 6 and 7 the finger 18 being in contact with the plate 17. The high and low portions 55 of the third rail are very short as compared to the normal or medium height and by the construction just described the shoe 1 raises and lowers as the case may be in passing over the elevated and lowered portions 60 of the third rail, and by such movement unlocks the main switch P , moves the same upward or downward, then relocks it through the medium of the locking finger α , which moves forward under the influence of 65 the spring α^4 . As the shoe 1 moves onto the

normal elevation of the third rail the switch is left in a locked condition, while the shoe travels on the normal or running portion of the third rail, and thus the main switch is locked in either its high or low positions, 70 even while the third rail shoe and the arm P^1 take a central position, as shown in Fig. 4, due to the travel of the shoe on the normal portions A^4 of the third rail. The shoulders P^2 are spaced apart to permit the arm P^1 to raise and lower slightly without affecting the main switch P .

Referring now to Fig. 1, S designates a direction switch which is thrown into either one of two positions, according to the direction the engine is running. This direction switch carries a series of blades 28, 29, 30 and 31 adapted to make contact with a series of corresponding sockets or plugs 24, 25, 26 and 27 indicating the direction "east" or "north", and said blades are also adapted to engage with a series of sockets 32, 33, 34 and 35 indicating the direction "west" or "south". The sockets 13 and 24 are electrically connected by a line 13^a, and the 80 sockets 4 and 32 are electrically connected by a line 4^a. The sockets 14 and 33 are electrically connected by a line 14^a, and the sockets 5 and 25 are electrically connected by a line 5^a. The sockets 15 and 34 are electrically connected by a line 15^a and the 85 sockets 6 and 26 are electrically connected by a line 6^a. The sockets 16 and 27 are electrically connected by a line 16^a and the sockets 7 and 35 are electrically connected by a line 7^a. R designates a cut out switch by means of which all connection may be established or severed between the signaling apparatus in the locomotive cab and the track. This cut out 90 switch carries a pair of blades 38 and 41 adapted to engage respectively with a pair of sockets 42 and 43, located on one side, and said switch also carries a pair of blades 39 and 40 adapted to engage respectively in a 95 pair of sockets 36 and 37 located on the opposite side. The various other signaling devices and the like, which are located in the locomotive cab comprise a warning lamp F , and a warning semaphore FF , for indicating the presence of a train two blocks forward in either direction, a danger lamp G and a danger semaphore G^1 for indicating the presence of a train on the next block ahead, a warning bell I , air or steam cut 100 off valve W , controlled by a motor W^1 , a reminder lamp K , arranged to burn or light up when the engineer has manually thrown his signaling apparatus out of connection, an engineer's telephone C , a relay L , for controlling the warning and danger solenoids D and E , a release lever J , by means of 105 which the engineer may stop the bell from ringing, and prevent the air being applied, and the steam cut off, high resistance coils 110

115

120

125

130

A, which may be supplanted by a battery and said resistance coils placed in the track blocks at the points indicated by the batteries a^2 , a^3 , a^4 , and a^5 , (Fig. 8), an indicator H, which shows whether or not the relay L is held by the line battery or by the engine battery, and the fuse Z.

The resistance coils A are variable in character. They are in series with those of the track, but as the resistance of the track coils is not variable, it is desirable to have variable coils on the engine so that on wet days and when there is considerable track leakage, said resistance coils can be reduced in resistance and the current through the main relay L correspondingly increased. These coils may take the form of a rheostat or any other convenient form of variable resistance. There are resistance coils in the track at all times whether or not the batteries are located in the track blocks or in the engine, but if the batteries are in the engine, they may replace coils A, or be placed in series with these coils for the necessity for coils A lessens with this method.

Where the batteries are in the engine, as shown in Fig. 13, the current from said batteries flows to and through rail A^1 , track resistance A opposite rail A^2 connection F^1 portion A^4 of the third rail, then through relay L back to the battery and as long as the track is clear, relay L (with its contacts reversed) is not excited, due to the fact that the track resistance is too high to allow sufficient current to flow through relay L, but as soon as a pair of trucks come onto that block (which trucks are of practically no resistance) the joint resistance of these trucks and track resistance coils is so low that a strong current flows through the relay L, thereby exciting the same and gives the necessary warning. Current flows through relay L all the time in this construction as long as the relay is in series with the track coils and the presence of this small current is shown in indicator H, but the current is too weak to work relay L.

Arranged for sliding movement upon the main track rails A^1 and A^2 are shoes 2 and 3 carried by vertically yielding rods 2^a and 3^a, and which rods are supported by a part of the front truck. The shoe 2 is electrically connected to the blade 9 of the main switch P by a line 23, and a branch line 23^a leads from the line 23 to a contact point 50 adjacent the telephone C. The shoe 3 is electrically connected to the blade 10 of the main switch P by means of a line 21, and a branch line 21^a leads to a contact point 51, adjacent the contact point 50, and operating between the contact points 50 and 51 is a switch 49. This switch 49 controls the path of the current to one or the other outer rail contact shoes for the purpose of establishing the telephone circuit, and where a

train is running east the engineer must throw the switch 49 into contact with the point 50 when it is desired to use the telephone on the locomotive, and thus the current is caused to pass through the conductors 23^a and 23 leading to the shoe 2, which is on the right hand or bonded rail A^2 . These conditions are practically reversed when the engine is running west, and under such conditions the switch 49 is shifted to the point 51 to send the current to the shoe 3 which is traveling on the bonded rail A^2 when the engine is running west.

While I have shown and described the parts 2 and 3 as shoes, it will be readily understood that said parts may, in some instances, be in the form of brushes or of wheels mounted on a suitable axle carried by the locomotive and which wheels are insulated from one another.

A tube Z^a extends from the box 1^b to the signal board located in the locomotive cab, and all the wires which electrically connect the parts within said box and the devices on the signal board are contained in this tube. The various lines and electrical connections between the box and the signal board are diagrammatically illustrated in Fig. 1, and are hereinafter specifically referred to in the tracing of the various circuits.

Assuming that a locomotive is positioned on the left hand or west end of block 5, and facing toward the left or "west" (Fig. 8) with the third rail shoe 1 resting on the normal portion of the third rail, and the corresponding track rail shoe resting upon the bonded track rail A^1 , it will be seen that there is an electric current passing through the two shoes, and although the locomotive is located on block 5, it is receiving current from block 6, owing to the connection F^1 at the left hand end of block 5. If an engine were on block 6, and facing block 5, said engine will short circuit the battery A^7 in block 6 through the wheels and axles, and as a result the current through the shoes of the locomotive running onto block 5 will be broken. In like manner any locomotive on block 5 is short circuiting the battery on said block through the locomotive wheels, and axles, and the engine on block 6 receives no current when it reaches the right hand half of block 6. Should an engine be located on the east or right hand end of block 5 facing left (or west) with its third rail and left track rail shoes connected to an ammeter, the same would show practically no current if any of the wheels of the engine or following cars were still remaining on block 4. As the engine must necessarily go from block 4 to block 5 in moving west this condition is bound to occur, and as a result the engine would short circuit its own indicators, thereby giving a false warning. To overcome such a condition the indicators must be held

up automatically by batteries on the engine while the same traverses the first half of each block. These batteries B (Fig. 1) are located on the engine and control the relay L. The parts A⁵ and A⁶ of the third rail are arranged so that the third rail shoe in moving upwardly or downwardly will throw the main switch P into the correct position for this condition. Where this is accomplished the engine does not short circuit the battery which controls the relay L, but in running over the first half of each block the relay L is held closed by the engine battery B, and in running over the second half of the block, the relay L is held closed by the battery on the next block ahead. An engine resting on any part of any one block short circuits the battery in that block and prevents an engine coming from front or rear, from getting the necessary current to hold the signals in a position indicating safety, hence said engine is protected from front and rear. If under such conditions described for traveling "west" an engine were to travel east it would be constantly short circuiting itself, and throwing its own signals. To overcome such condition the direction switch S is provided for restoring the normal conditions, corresponding to the movement "west" of the engine on the track.

In order that the signals, including the semaphores, bell and lights be all held at "safe", a current of electricity must be passing through the relay L, either from one of the track batteries, or the engine battery as the case may be. If for any reason this current fails, the relay L opens, thereby breaking all the circuits holding the semaphore arms at "safe" and closes the circuit which rings the bell, lights the lamps and operates the motor used to apply the air and cut off the steam. The semaphores rise to warning and danger positions by the gravity of counter-weights C on the ends of the semaphore arms opposite the disks, and the red or danger disk is in front of the yellow or warning disk so that when danger occurs, although they both rise the red disk is in front of, and masks the yellow disk. When the red disk is up the yellow or warning light can not burn, owing to the arrangement of contacts governed by the solenoids D and E. In order that the yellow light can burn, and the yellow disk show, the red or danger disk must be held down in a position of safety. The yellow or warning disk is thrown upward into a warning position only when the third rail shoe moves onto the higher position A⁶ of the third rail while the engine is running west, or while the engine is running east and the shoes are on the lowest portions A⁵ of said third rail. If under such conditions the current fails to enter the third rail shoe the warning disk FF is thrown while the red disk is held by

reason of the contact of the finger 18 with either one of the contact plates 17 or 19. The station master can stop an engine by breaking the circuit through the station on any block desired, and when the engine approaches that block it fails to get the necessary current and consequently the danger signals are displayed in the engine cab.

The fact that an engine runs half a block with all of its signals thrown out of control by the line does not leave the engine unprotected, for as it will be hereinafter shown that by action of the track relay magnets Q it is impossible for two engines to approach each other or for one to approach another without the warning signals being displayed in the cabs of both engines.

Assuming that an engine is running west on the east half of block 3 with the main switch P low and the third rail shoe 1 traveling on the normal portion of the third rail, the circuit, comprising shoe 1, line 53, telephone hook 52 carrying contact points, and performing the function of a switch, line 52^a containing the resistance A, blade 11, 85 socket 6, line 6^a, and socket 26 is open, owing to the fact that the direction switch S is elevated, hence there is no flow of current through the circuit, just traced. The circuit comprising the right outer track rail shoe 2, line 23, blade 9, socket 5, line 5^a, 90 socket 25 is open, owing to the elevated position of the direction switch, and the branch circuit through the line 23^a to the contact point 50 is open owing to the position of the switch 49, hence there is no-flow of current through these circuits. The circuit comprising the left outer rail track shoe 3, 95 the line 21 and blade 10 is open, and in a like manner the circuit comprising the line 21^a and contact point 51 is open owing to the central position of the switch 49, and thus there is no flow of current through these circuits, hence all three of the shoes are out of circuit. The relay L is closed by current 100 from the battery B as follows: This current flows from the positive pole of the battery B, through line 44, through coil 62 of relay L, from thence through the opposite coil 63, through line 60, line 87, to the indicator H, 105 line 88, blade 31, socket 35, line 7^a, socket 7, blade 12, line 12^a, blade 41, socket 43, line 46 and back to the negative pole of battery B. Branch circuit from line 46 through line 46^a, 110 to socket 36 is open and branch circuit from line 88 through line 95 to blade 39 is likewise open. Branch circuit from line 88 through line 48, reminder lamp K, line 47 to blade 40 is open and branch circuit through line 60, to blade 29, socket 33 and line 14^a, to 115 socket 14 is open, hence no-flow of current. Branch circuit through line 44^a, from line 44 to socket 37 is open, and likewise the circuit comprising line 45, blade 38, socket 42, line 99, indicator H, line 98, blade 30, socket 120 125 130

34, line 15^a and socket 15 is open, and consequently there is no flow of current therethrough. Thus the battery is discharging its current through relay L, keeping the 5 same closed, and said current passes through the indicator H thereby recording the engine's current, and all other paths or circuits are open, and consequently there is no flow through said open circuits. Under such 10 conditions the engine is running blind with all its signals held at "Safe" and the indicator H showing the engineer the means or reason why the signals are so held. As long as the above conditions exist the engineer 15 can receive no warning of the presence of another engine. The engine and car axles are, however, short circuiting the battery a³, that is, said battery is discharging its current through line D⁷, switch C³, indicator B³ 20 and line B⁷ to the continuous rail A¹, along this rail to the left hand car wheels, across axles to right car wheels, through the right hand rail section of block 3 and back to the opposite pole of the battery a³. The presence 25 of this particular engine on this particular block is, therefore, indicated in the station and such indication is independent of the third rail contact with the third rail shoe, or either of the outer rail shoes, thus 30 the station agent is notified of the presence of an engine on block 3; and this indication continues as long as any part of the engine or train is on said block. While the train is 35 in this position the station master has no control of the train, for if he breaks the circuit the flow of current through the wheels and axles is stopped, thus not affecting the indicators on the engine. While the wheels and axles of this engine are short circuiting 40 battery a³ it will be readily understood that a train approaching from front fails to get current from the battery a³, and said approaching engine is thereby warned; hence the engine on block 3, though running 45 blind, is safe.

The engine continuing west, or toward the left on block 3, passes over one of the lower portions A⁶ of the third rail, and the third rail shoe consequently follows the downward 50 trend of said rail, but in view of the fact that the third rail shoe passed over a corresponding low portion of the third rail at the beginning of block 3, there will be no change of position of the main switch P. 55 As the train moves on to the west half of the block 3, the third rail shoe passes on to one of the high portions A⁵ of the third rail, and as a result, the third rail shoe, the rod 1^a and the switch arm P¹ are elevated, consequently lifting the main switch P into the upper set of plugs or sockets, and said main switch is locked in its elevated position by the finger X, and finger 18 is moved into contact with the plate 19. Under such 60 conditions, if block 4 is occupied by a train, a

warning signal will be thrown first, followed immediately by the danger signal, but if block 4 is clear, the current from battery a⁴ flows through line D⁸, switch C⁴ to the indicator B⁴, from thence to line B⁷ to the bonded track rail A¹, thence through the shoe on said bonded rail, thence through line 21, blade 10, socket 14, line 14^a, socket 33, blade 29 and line 60 to relay L, thence through line 44, line 45, blade 38, socket 42, line 99, indicator H, line 98, blade 30, socket 34, line 15^a, socket 15, blade 11, line 52^a, resistance coil A and line 53 to the third rail shoe 1 and thence through line F¹ back to battery a⁴, under which conditions the relay L is maintained in a closed position and the signals are held at "Safe". As the engine advances toward block 4 and the third rail shoe passes on to the normal portion of the third rail of west (left) half of block 3, the only change that occurs is the breaking of the contact between the parts 18 and 19, thereby allowing the danger semaphore to be thrown if danger from an approaching train exists. The main switch P having been thrown into a high position and so locked, maintains such position, and the engine moves forward to the left hand end of block 3. Thus the engine is running west with the main switch P in a high position, and the third rail shoe is on a normal portion of the third rail, with the current flowing from the third rail shoe through the high resistance, relay and indicator to the left hand outer rail shoe, and under such conditions, the relay L is kept closed and the indicator H shows that the current is coming from the line. When one of the circuits through the indicator H is closed, the hand thereof is moved toward the left, and when the other circuit is closed the hand of the indicator is moved toward the right. Thus said indicator shows that the engine is getting its current from one of the track batteries or that it is getting current from its own battery, and therefore running "blind." The presence of a train on block 3 is indicated by the station indicator B³, but as soon as the engine reaches the left half of block 3 it begins to receive its current from block 4, and this current must first pass from the station indicator B⁴ before reaching the engine. As the station indicator B³ has been indicating for some time the presence of a train on block 3 and while still doing so indicator B⁴ begins to indicate it is plain to the station master that the train is still on block 3, but has passed the center of this block and is drawing its safety current from block 4. This indication is verified inasmuch as indicator B⁵ has not indicated any train on block 5 which might be drawing current from block 4 ahead of it. An engine on the left half of any one of the station blocks, as block 3 for instance, is drawing current from two different sets of

track batteries, provided the engine is running toward the left hand, thus short-circuiting the track and block on which it is standing, and in doing so the current passes 5 through the engine wheels and axles and through the station indicator of that block. It is also drawing current from the track battery of the block ahead of it (in this case block 4), and in doing so through the station indicator of this block and through one outer rail and the third rail, consequently the engine is indicating on station indicators B³ and B⁴ its presence on block 3, and shows that it is in communication with block 4. 10 If the station agent opens the switch D⁴, the circuit which the engine depends upon to hold its signals at "Safe" is broken and the engineer is warned. When the engine travels to the extreme left hand end of block 3, the third rail shoe 1 is resting on a high portion A⁵ of the third rail which is connected forward to the corresponding high portion at the middle of block 4. The current passing from said shoe through this 15 portion of the third rail, passes through wire F¹ connected to this particular portion of the third rail, thence to outer rail A² battery a⁵, thence through the connections in the station back to bonded rail A¹, thence 20 through the engine to the third rail shoe. This current is instrumental in holding up the yellow disk, keeping the yellow lamp from burning. Thus it is impossible for two engines to approach one another without the 25 engineer being warned in plenty of time, even if the other engineer is running without signals, and the engineer on the second engine is always warned in plenty of time and at a safe distance. The engine on the west or 30 left-hand half of block 3 is receiving current from block 4, providing said block is clear, and consequently the engineer can readily tell whether or not block 4 is clear. As the engine is about to run off block 3, 35 the third rail shoe runs on to a high portion of the third rail, thereby giving a momentary contact and consequently getting current from block 5 ahead, if block 5 is clear. If the engine gets this current and no signals 40 are thrown, then the engineer knows that the block 5 is clear at that instant and consequently he knows that he may safely run the engine on to the east end or blind half of block 4 and the signaling apparatus will 45 again be in communication with block 5 just after the engine has passed the center of block 4 by reason of the third rail shoe riding onto the high portion A⁵ of the third rail at the center of said block 4. The engine 50 now runs on to the right hand or east end of block 4, and conditions are exactly the same as hereinbefore described when the engine occupied a position on the right hand or east end of block 3. 55 Assuming that the engine has just passed 60 the center of block 4 and is moving toward block 5 with the third rail shoe on the high portion A⁵, at the center of said block 4 and when so positioned the current from track battery a⁵ on block 5 passes through conductor F¹ to the left hand portion of the third rail A² in block 4 and passes from thence through the third rail shoe, as hereinbefore described, into and through relay L, but if it fails to do so, relay L, in opening 65 opens the yellow signal circuit and not the red one, due to the fact that contact is made between the parts 18 and 19. The engine consequently runs past the high portion of the third rail and the third rail shoe thereby runs onto the normal portion of the third rail and contact between the parts 18 and 19 is broken and if current does not flow into the engine, the red signal is thrown. (These 70 circuits are more fully traced in the descriptive matter on the last half of page 21 of this specification and the first half of page 22). In referring to the drawings in connection with this description it should be borne in mind that shoe 2 is the right hand shoe of an engine moving toward the west or left hand of Fig. 8, thus the shoe 2 is always on the side of the engine occupied by the engineer, viz; the right hand side, and the shoe 3 is on the left hand side of the locomotive which is the side occupied by the fireman. 75

If an engine approaches the first engine from the west, the conditions just described exist, if the direction switch S on said second engine is thrown downward to the east position; and if the west-bound engine is on block 3 and the east-bound engine on block 5, both engines are trying to get current from block 4, but such action is impossible 80 by reason of the track relay magnets Q adjacent the battery A⁴. In case two approaching engines reach warning blocks at practically the same time the first engine to reach its block uses the current from ahead, 85 and breaks the current for the other engine through action of the track relay magnets Q. The first engine gets no warning at this point under such conditions, but the second engine gets its warning and stops. The 90 first engine continues until it gets into communication with the battery on the block on which the second engine is standing, and failing to get current, stops. Thus the two engines are stopped approximately a block 95 apart. Due to the practically instantaneous action of electricity, and the responding of a magnet relay, it is impossible for two different engines to use one battery at the same instant. 100

An engine traveling east upon the track is under the same conditions as just described, providing the direction switch S is thrown to the position indicating east. This action places the right outer rail shoe 105

and the third rail shoe in-circuit and disconnects the left outer rail shoe. Such movement also throws the signal out of service with the line batteries on the half of the block onto which the engine first runs, that is, when the third rail shoe and the switch P are high. A failure on the part of an engineer to properly throw his direction switch will result in causing his engine to short circuit itself, thereby giving warning.

In case the direction switch S is improperly set, the circuit through relay L is broken, and as a result, said relay fails to hold the signal at "Safe." The circuit through relay L is dependent upon the correct positioning of both the direction switch S and the main switch. As the main switch correctly positions itself due to the undulation of the third rail an error can only be made in the other, that is, the direction switch. Hence, if the direction switch S is incorrectly positioned, the relay L does not get current, and as a result, the warning signals are thrown. If the direction switch S is correctly positioned, the circuit through relay L is never broken unless there is danger ahead, it being held part of the time by the track batteries, and when the train is in the wrong part of the block for the track batteries to hold, then the engine battery B is in service and the change is made without breaking the circuit. Neither the local engine battery B or any track battery can complete its circuit through relay L unless both the main switch and direction switch are correctly positioned. Battery B is made use of for the "blind" halves of the blocks only.

Referring now to Fig. 14 the right hand magnet of the relay Q acts with the right hand section of rail A² by reason of the connections Q¹ and Q², and the left hand magnet of this relay acts with the left hand section of the rail A² by reason of the connections Q³ and Q⁴. If the circuit between the right hand section of rail A² and the bonded rail A¹ is closed the path is established for a current to flow through the right hand magnet thereby energizing the same and drawing down the armature, thus breaking the path of any current to the left hand section of rail A² and as long as the circuit is established between the bonded rail A¹ and the right hand section of rail A², the current can not cross the open space between the armature of the right hand magnet of the relay and the contact point from which connection Q⁴ leads, and thus the current is prevented from passing into the left hand block of rail A². This condition is graphically illustrated in Fig. 15, where a car axle and wheels are shown in dotted lines, and form a connection between the bonded rail A¹ and sectional rail A², and

the path of the current is shown by arrows. The car axles and wires are short circuiting the battery as indicated by the arrows, and no engine which may come onto the opposite end of the blocks, as, for instance, at Y can get any current, and said last mentioned engine is, therefore, warned. The first engine, or the one at the right is not yet warned, but will be as soon as it makes connection with the third rail section A².

In an engine running east, with the main switch low and the third rail shoe on the normal portion of the third rail, we have the following circuit: from the third rail to the third rail shoe 1, line 53, switch hook 52, line 52^a in which the high resistance A is located, blade 11, socket 6, line 6^a, socket 26, blade 30, line 98, indicator H, line 99, socket 42, blade 38, line 45, line 44, relay coil 62 of relay L, coil 63, line 60, blade 29, socket 25, line 5^a, socket 5, blade 9 and line 23 to the shoe 2 on the right outer rail A¹, and thus the current through this circuit passes from the third rail shoe to the right hand rail shoe, and in so doing, passes, through the indicator H, relay L, and also through the fuse Z and high resistance A.

Where an engine is running east on the first half of a block with the main switch P high and the third rail shoe on the normal portion of the third rail, there will be a flow of current from the positive pole of the battery B through line 44, coil 62 of relay L, coil 63, line 60, line 87, indicator H, line 88, blade 31, socket 27, line 16^a, socket 16, blade 12, line 12^a, blade 41, socket 43 and line 46 back to the negative pole of battery B. When the engine was on high block A², solenoid E was held up by a current through line 76, line 80 to the negative pole of the battery N from the positive pole of said battery, through line 61, through contact finger 18, and contact plate 19, line 20, line 59 and line 77, which is connected to said solenoid E. When the armature of the relay L is drawn downward, and contact 18 and 19 is broken, the current just described passes from the line 61^a through contact points 57 and 58, and from thence through line 59 to line 77. Under such conditions, as long as contact points 58 and 57 are closed, the solenoid E is held up, but when the circuit between the points 57 and 58 is broken, solenoid E drops, unless the contact finger 18 is making contact with either one of the plates 17 or 19. Solenoid D is held up by a current passing through line 78, line 65, battery M, line 64, line 22^a, contact points 55 and 56, line 96 and line 79, back to solenoid D. This condition prevails as long as the main switch P is high and the engine is running east, and with the parts in this position, the current passes from line 22 to blade 8, socket 13, line 13^a, socket 24, and blade 28, thence through line 28^a back to

line 79, thus solenoid D is holding its core up independently of the action of relay L.

- When the engine is running west, with the main switch low, the current passes from blade 8 to socket 4, through line 4^a, socket 32, blade 28, and back through lines 28^a and 79, to the solenoid D. When the engine is running west, with the third rail shoe high, or while running east, with the third rail shoe low, the solenoid D may drop when the circuit between the points 55 and 56 is broken, because the circuit through lines 22 and 28^a is now broken; hence solenoid D always drops with the dropping of solenoid E, and in like manner, solenoid E drops with solenoid D, unless the contact finger 18 is making contact with either one of the plates 17 and 19. When the core of solenoid E drops, contact between the points 74 and 75 is broken, thereby preventing current from passing through the warning lamp and lighting the same, and such action makes contact between the points 72 and 68, and 73 and 69; consequently, current flows from the positive pole of the battery N through line 79^a, contact points 69 and 73, line 97, line 91, line 89, through the bell I, through line 90 to the contact point 93, contact point 94, line 85, and back through the line 80 to the negative pole of battery N. A branch circuit passes from line 79^a through the contact points 68 and 72, line 83, danger signal lamp G, line 84, and back to battery N through line 80. When both cores of solenoids D and E have dropped, current from the battery N, through line 79^a, contact points 67 and 71, and lines 91 and 89, passes to the bell I to ring the same. Even though contact points 70 and 66 are in contact, the circuit through line 81, warning lamp F, line 82 and contact point 75 is open, hence this warning lamp does not burn. With the core of solenoid D dropped and with the core of solenoid E elevated current flows from battery N, through line 79, contact points 67 and 71, through line 91, line 89, through bell I, line 90, contact points 93 and 94 of hand switch J, and from thence through lines 85 and 80, back to battery N. At the same time, current from battery M flows through line 64^a to contact points 66 and 70, line 81, to the warning lamp F, line 82, to contact points 75 and 74, and from thence through line 65^a back to battery M. As long as the pointer on indicator H points to "Line", and the signals are not set, the engineer knows that the track on which his engine is running is absolutely safe, as far as other trains are concerned, for the pointer indicates "Line" only when the current is being taken from the next block ahead or the second block ahead.

In practice the cores of the solenoids D and E will be constructed so that when they fall they will do so with a slow or delayed

action which result can be accomplished by the use of dash pots or compressed air cylinders. This slow movement takes place in order that said cores will not drop their entire length when the third rail shoe instantaneously loses contact with the third rail. Where such action occurs the solenoid core will drop a short distance, but would be caught and pulled upward again before setting the warning signals. The upper ends of the cores of these solenoids are adapted to be held locked after dropping, by means of spring held catches D¹ and E¹, and which catches are released by means of manually operated cords D². Such construction holds the warning and danger semaphores FF and G¹ up, and therefore, visible to the engineer when said semaphores have been actuated, and they will be so held until the engineer releases them by manipulating the cords D².

Figs. 5 and 6 illustrate the third rail shoe at its highest and lowest points respectively, and when the shoe is in either one of these positions, a connection is made between the finger 18 and either the contact plate 19 or contact plate 17, and which connection is not made when the shoe is on the normal portion of the track, as seen in Fig. 4. This connection between the finger 18 and plates 19 and 17 is made to establish the circuit to give the warning signals and not the danger signals. If the current from the line is broken when the shoe is on a high portion of the rail and traveling west, or upon a low portion of the rail and traveling east, the warning or yellow semaphore falls, but the danger semaphore is held up by the local engine current. The motor W¹ receives current and starts running when the signals are thrown, and by proper gearing, this motor actuates the air or steam valve W. Although there are three contact shoes or wheels on the engine for the third rail and the two track rails, only two of said wheels are in service at one time, and one of these two is always the third rail shoe, while the other one is the outer rail shoe which is resting on the continuous bonded rail A¹. The other outer rail shoe, or the one resting upon the rail A² which is divided into sections or blocks, is always disconnected from the batteries and signals, as the wire from said shoe always runs to an open plug or socket. An engine on any one of the blocks will short-circuit the line battery on that block through the corresponding indicator in the station, thereby indicating the presence of the engine on that block as long as it remains on any portion thereof.

I have illustrated Fig. 8 as being equipped and wired for a single track road, that is, for a road on which trains run in either direction.

Fig. 9 illustrates the wiring and arrangement

ment of blocks for a double track, and it will be noticed in this double track arrangement there are no warning blocks, and no track relay magnets, as the same are not necessary when the trains run in one direction only on the separate tracks. The single and double track arrangement illustrated in Figs. 8 and 9 can be readily combined, if desired, that is, running from a single track to a double track, or vice versa. The third rail arrangement of the single track illustrated in Fig. 8 is merely a combination of the rails and wiring of the double track with the warning blocks, and track relay magnets, added.

Where my improved system is utilized in connection with double track, as shown in Fig. 9, it is not necessary to arrange the third rails with the high and low portions A⁵ and A⁶, but as it is essential that the engine enter the double track with its main switch D properly thrown it is necessary to provide the third rail at one end with a high or low portion and the rail shoe 1 in passing over this high or low end portion of the third rail properly sets the main switch P. An engine traveling over one portion of a double track receives current exactly the same as an engine operating on a single track provided the third rail shoe has lifted or depressed the main switch P into correct position on starting out, and this is accomplished by elevating or depressing a portion of the third rail at the beginning of the double track in either direction.

Fig. 10 illustrates a switch or siding properly equipped and wired so as to be used in connection with my improved system, and in said figure the switch is shown as being set for a train to take the main line. The siding wires are broken between the contact points arranged on the switch handle, therefore an engine on the siding can get no current and its signals are thrown. Located adjacent to one of the track rails of the siding close to the main line rail is a short rail section 100 arranged to make contact with one of the wheels of a car or engine when the same is on the siding and standing too close to the main line. When such condition occurs, a short-circuit to the main line is made, thus warning a train approaching on the main line so that the same will not strike the car on the siding which stands too close to said main line.

Fig. 11 illustrates a single track crossing arranged and wired in accordance with my invention for the mutual protection of two trains approaching from any two directions.

In Fig. 16 I have diagrammatically illustrated the track relays necessary for a crossing, and in this construction a current from rail A² passes through conductors V¹ and V², the relay magnet V³ thereby draw-

ing down the armature of said magnet and consequently breaking the current to the three other magnets, therefore, no current can get to these magnets, and their armatures are held up so that the path of the current from bonded rail A¹ can not be broken by them, and thus the magnet V³ breaks the flow of current to the other magnets, but not to its own.

Figs. 12 and 13 illustrate an arrangement whereby the batteries may be placed in the track and the resistance on the engine, or such arrangement reversed. The results attained from these two different arrangements are practically the same. For all practical purposes, it is preferable that the batteries be placed in the track.

As shown in Fig. 13, the track relays Q are omitted and the engine battery is placed in circuit at practically the same point occupied by the resistance A, shown in Fig. 1, said resistance being eliminated from the circuit. The correct polarity can be given by means of additional polarity changing switch blades and sockets on the direction switch S, for as the train changes direction of run switch S must be thrown by hand by the engineer, and when this is done, the polarity of engine battery will be reversed. The engine battery for the modified system must not be confused by the local engine battery B of the preferred form of the system, shown in Fig. 1. The local engine battery B in the preferred form illustrated in Fig. 1 must necessarily be cut out of circuit when the engine is on the "blind" half of the block or else sufficient resistance automatically placed in service with the battery to cut down the current through relay L. This can be accomplished by means of the automatic main switch controlled by the third rail shoe and the direction switch in much the same manner in which local battery B is cut into circuit automatically by the same switches. Whenever local battery B is in circuit with relay L the resistance A is out of circuit with this relay, and vice versa. Hence, if in place of the resistance A, a battery be substituted, this battery and the local engine battery B could never both be in circuit with relay L for other than a very minute period of time (on when the main switch is passing through the center of its arc of swinging movement) and the action of dash pots would prevent the signal from being thrown for this minute break in the circuit or the effect of counter currents.

When the track batteries are carried on the engine and the variable resistance A placed in the track circuit the engine battery B has no function as far as the control relay L is concerned, but still has the function of lighting the warning lamp K which

the switch R is thrown to "off" or down. Consequently the engine circuits would be simplified by omitting blades 39 and 41 of switch R; also blade 31 of switch S also 5 blade 12 of switch P, and likewise the circuits in which these parts are located. In this modified arrangement or where track batteries are replaced by track resistances, the control relay L acts in exactly the reverse 10 manner to that in which it acts in the preferred system, heretofore described, that is, relay L remains normally with its armature not attracted, and said armature is attracted only when the distant train short circuits a track resistance, thus allowing a strong current to flow through L and attract its armature. Consequently, the contacts 55, 56 57, and 58 of relay L must be so placed on the armature of L as to remain closed when the armature is not attracted, and be opened when magnet L attracts its armature. Thus it will be seen that by this modification the engine circuits have not been altered to any appreciable extent, nothing has been added, no indicator or other device has been altered and nothing omitted with the exception of a few circuits which are necessary in the operation of the preferred system.

30 The purpose of connecting the low portions A⁶ of the sectional third rail by the conductors F² is to practically prolong or extend the sectional third rail a half a block length so an engine will get a momentary warning as to the condition of any particular block a half a block length ahead. The telephone circuit includes track rail A¹, conductor 21⁴, contact 51, switch 49, instrument C, conductor 53, third rail shoe 1, third 35 rail A³, conductor F¹, track rail A², any one of the batteries A², A³, A⁴, A⁵, corresponding conductor D⁶, D⁷, D⁸, D⁹, corresponding switch C², C³, C⁴, C⁵, conductor E⁶, instrument E⁷ and back to rail A² by conductor 40 B⁷. When track batteries are used, said batteries are also used for obtaining current for the telephone circuit, which circuit thus becomes a common battery circuit and any type of common battery telephone can be 45 used. When track batteries are not used, but engine battery is used with resistance coils in the track, then a local battery should be used in the central station—(not shown) but the system still operates on the common 50 battery system with merely the position of the source of telephone electrical energy changed.

My improved signal system may be termed an open-closed circuit system, open in that 55 the batteries are not being used except when a train is in communication with them, and closed in that so long as a train is in communication with a block, the batteries are constantly discharging current. Such con-

struction makes the system economical as to 65 batteries and current consumed. The line wiring is reduced to a minimum, and only one rail and one wire are necessary throughout the entire length of track. The single wire is, of course, divided up into block sections F² 70 and F³, and the ends thereof connected to the various sections of the third rail. The system insures perfect safety for an engine or train, as far as other trains on the same track are concerned, for, as heretofore described, an engine may proceed with its signals indicating safety as long as current is supplied from the line batteries to so hold the signals, and if any of the connections are broken, or if there is danger from an 75 approaching train, the engineer is warned in ample time. Anything of a metallic nature resting across the outer rails will, of course, warn an approaching train, by reason of the short-circuit produced between 80 said outer rails. All switches and crossings must be properly set and clear, or, if not, the warning signals are displayed in the cab of an approaching engine. All signals and warning devices are located on a small 85 board immediately in front of the engineer, and for this reason can be readily observed and an accident cannot occur by reason of an engineer accidentally or wilfully running past a semaphore arm. The station agent 90 knows at all time the position of a train proceeding over the blocks of the track connected with his station, and the agent can stop the train on any block, and if desired, may communicate with the engineer by 95 means of the telephones located in the station and engine cab. If for any reason the engineer fails to observe the warning and danger signals, the air brakes will be applied and the steam cut off from the engine 100 by the action of the motor W¹, which is set in operation when the signals are thrown, but which motor runs for a short time before completely turning on the air and the steam valves.

110 While some of the batteries, resistance coils, relay magnets, etc., are shown as being placed between the outer rails it should be observed that this is for diagram showing only, and they may be placed at any 115 point convenient to the track and the lead wires connected to the rails at the points shown.

I claim:

1. In a railway signal and locomotive controlling system, signalling and indicating devices carried by the locomotive, electrical circuits in which said signalling and indicating devices are located, a switch for making and breaking said electrical circuits, a railway track divided into blocks, a sectional third rail divided into blocks corresponding to the blocks of the railway track, portions 120

125

of which sectional third rail in each block are elevated and other portions being depressed with respect to the main portion of each block of said third rail, a shoe carried by the locomotive and traveling on said third rail for actuating the switch, indicators in a way station which indicators are electrically connected to the blocks of the railway track, means controlled by said connections whereby said indicators are actuated for indicating the presence of the locomotive on the blocks, a telephone on the locomotive, a telephone in the way station, and means whereby the telephones are placed in circuit through said shoe, third rail and track.

2. In a railway signal and locomotive controlling system, a railway track divided into blocks, a third rail divided into blocks corresponding to the blocks of the railway track, each block of the third rail being divided into sections insulated from one another, certain of the sections of each block being elevated and certain of said sections being depressed with respect to the plane occupied by the main body portion of said third rail by the locomotive, indicators located in a way station, and connected to the blocks of the railway track, electrical connections between the signaling and indicating devices and the sectional third rail, a switch carried by the locomotive for opening and closing the electrical connections in which the signaling and indicating devices are located, and a shoe included in said electrical connections carried by the locomotive and adapted to travel upon the third rail for opening and closing the switch.

40 3. In a railway signal and locomotive controlling system, a railway track divided into blocks, a third rail which is divided into blocks corresponding to the blocks of the railway track, each block of said third rail being divided into sections insulated from one another, and certain of the sections of each block being elevated and other sections depressed with respect to the plane occupied by the main body portion of said third rail by the locomotive, electrical connections between said signaling and indicating devices and the sectional third rail, indicators located in a way station, and electrically connected to the blocks of the railway track, a switch carried by the locomotive for opening and closing the electrical connections in which the signaling and indicating devices are located, a shoe carried by the locomotive and included in said electrical connections adapted to travel upon the third rail, said shoe being connected to the switch for the purpose of raising and lowering the same as said shoe passes over the raised and de-

pressed portions of the third rail and means whereby the switch is held after movement to either one of its set positions.

4. In a railway signal and locomotive controlling system, a railway track divided into blocks, a third rail which is divided into blocks corresponding to the blocks of the railway track, each block of said third rail being divided into sections insulated from one another, and certain of the sections of each block being elevated and other sections depressed with respect to the plane occupied by the main body portion of said third rail by the locomotive, indicators located in a way station, and electrically connected to the blocks of the railway track, a switch carried by the locomotive for opening and closing the electrical connections, in which the signaling and indicating devices are located, a shoe carried by the locomotive included in said electrical connections and adapted to travel upon the third rail, said shoe being connected to the switch for the purpose of raising and lowering the same as said shoe passes over the raised and depressed portions of the third rail means whereby the switch is held after movement to either one of its set positions, and manually operated means for raising the shoe free from the third rail.

95

5. In a railway signal, and locomotive controlling system, a railway track, a third rail adjacent to the rails of said railway track, portions of which third rail are elevated and other portions being depressed with respect to the plane occupied by the main body portion of said rail, signaling and indicating devices carried by the locomotive which travels on the railway track, electrical circuits in which said devices are located, a source of electrical energy for said circuits, a switch located in and controlling said circuits, and a shoe connected to said switch, which shoe travels upon the third rail and raises and lowers the switch as said shoe passes over the elevated and depressed portions of said third rail.

6. In a railway signal, and locomotive controlling system, a railway track, comprising a continuous rail and a sectional rail, which track is divided into blocks each composed of a plurality of sections, a series of indicators in a way station corresponding to a certain number of blocks of the railway track, each indicator being electrically connected to the rail sections of a corresponding block of the railway track, a source of electrical energy for the electrical connections of each indicator, an electrical connection from all of the indicators of the way station to the continuous rail of the track, a telephone in the way station, a normally open circuit in which said telephone is lo-

11

12

13

cated, which circuit is connected to the conductor from the continuous track rail to the indicators and switches located in said circuits for connecting the telephone with any 5 block section.

In testimony whereof I hereunto affix my

signature in the presence of two witnesses,
this twenty-fourth day of December, 1910.

GEORGE R. GUILD.
